**HOUSING FOR HUMIDIFIER OR DEFLECTOR
OR THE LIKE**

Salvatore R. De Marco, Cherry Hill Township, Camden, County, N.J., assignor to Moisture Vent, Inc., Woodbury, N.J.

Continuation-in-part of design application Ser. No. 24,873, Sept. 8, 1970. This application Feb. 22, 1971, Ser. No. 117,857

Term of patent 14 years

Int. Cl. D23—04

U.S. Cl. D23—146

FIG. 4

FIG. 3

FIG. 5

FIG. 6

FIG. 7

FIG. 8

FIG. 9

FIG. 11

FIG. 10

FIG. 12

FIG. 1 is a front perspective view of a housing for a humidifier or deflector or the like showing my new design;

FIG. 2 is a side elevational view thereof on a reduced scale;

FIG. 3 is a rear elevational view thereof on a reduced scale;

FIG. 4 is a bottom plan view thereof on a reduced scale;

FIG. 5 is a front perspective view of a second embodiment of my new design;

FIG. 6 is a side elevational view of the embodiment shown in FIG. 5;

FIG. 7 is a rear elevational view of the embodiment shown in FIG. 5;

FIG. 8 is a bottom plan view of the embodiment shown in FIG. 5;

FIG. 9 is a front perspective view of a third embodiment of my new design;

FIG. 10 is a side elevational view of the embodiment shown in FIG. 9;

FIG. 11 is a bottom plan view of the embodiment shown in FIG. 9, and

FIG. 12 is a rear elevational view of the embodiment shown in FIG. 9.

This is a continuation-in-part of design application 24,873, filed Sept. 8, 1970 and now abandoned.

I claim:

The ornamental design for a housing for humidifier or deflector or the like, as shown and described.
